UNITED STATES PATENT OFFICE.

FRANK SHORT, OF SCHENECTADY, NEW YORK, ASSIGNOR TO GENERAL ELECTRIC COMPANY, A CORPORATION OF NEW YORK.

MAGNETIC CONNECTION.

1,168,037.

Specification of Letters Patent. Patented Jan. 11, 1916.

Application filed August 15, 1914. Serial No. 857,002.

To all whom it may concern:

Be it known that I, FRANK SHORT, a citizen of the United States, residing at Schenectady, county of Schenectady, State of New York, have invented certain new and useful Improvements in Magnetic Connections, of which the following is a specification.

My invention relates to the magnetic connection of rotary parts, and more especially to the connection or attachment of speed or revolution measuring, counting, indicating, or recording devices and the like to revolving shafts or other rotary members. In general, my invention not only permits the connection or application of speed indicators (as devices such as above referred to may be generically termed) to shafts to be made quickly and easily, but also relieves the operator of any trouble or attention in supporting the device or maintaining its connection. How these and other advantages can best be obtained in accordance with the invention will appear from the detailed description hereinafter of the best embodiments at present known to me, while its scope will be indicated in my claims.

In the accompanying drawing, Figure 1 shows in axial section one form of my connecting device ready to be applied to a shaft, and also a simple speed indicator ready to be connected to the shaft by means of the device. Fig. 2 is a tilted view of an accessory part. Fig. 3 is a mid-sectional view of a modified form of my connecting device.

In carrying out my invention, I employ a part adapted to be applied endwise to the shaft and comprising or constituting magnetic means for causing it to adhere to the shaft. With this magnetic part I combine or associate means for centering it with reference to the shaft. Ordinarily I prefer to make the magnetic part a permanent magnet of suitable strength rather than to produce the magnetic attraction electrically when the device is in use.

As shown in Fig. 1, the magnetic part is a cup-shaped piece 1 of permanently magnetic material such as steel, and the means for centering it with reference to the shaft is a center-punch piece 2 fitting more or less tightly in a bore in a central boss 3 in said part 1, but not so tightly as to prevent its shifting therein as hereinafter set forth.

This piece 2 may be of angular section or 55 may be otherwise positively prevented from turning in the part 1 if it is thought undesirable to rely on mere friction. One end of the center punch 2 is conically or pyramidal pointed at 4 so as to engage properly 60 in the counter sink or prick-punch mark 5 in the end of the shaft 6, while the other end has a sort of socket device 7 comprising a plurality of spring fingers for engaging the actuating member 8 of the speed indicator 9. 65 The bottom of the socket device 7 may be conical, or it may be pyramidal so as to engage the pyramidal end of the actuating member 8 to the best advantage. When the part 1 is applied against the end of a shaft 70 or the actuating member 8 of the speed indicator 9 placed in the socket device 7, the punch part 2 will yield lengthwise in either direction with reference to said part 1 as may be necessary. Under these conditions, 75 rotation of the speed indicator 9 as a whole with its actuating member 8 may be prevented by means of the ordinary weight of the parts, or by a special weighting, or even by a wire or the like securing them to any 80 convenient part or structure.

The part 1 is made cup-shaped in order that it may better retain its magnetism, just as magnets are ordinarily made horseshoe-shaped; and as the centering piece 2 will 85 preferably be made of steel or other ferrous metal so that it will be or become magnetized, the whole device is, indeed, in effect a sort of "horse-shoe magnet of revolution". When the device is applied to a shaft smaller 90 than the inside of the cup 1, the latter will go on the end of the shaft. Preferably a disk 10 of soft sheet iron (see Fig. 2) with a central hole for the part 2 will be provided to serve as a keeper when the device is not 95 in use.

In Fig. 3 the edge of the cup-shaped magnetic part 21 is extended inward to make it retain its magnetism better still, and the centering part 22 is urged outward or forward in the central boss 23 by a coil spring 24 acting between a shoulder thereon and a part 25 screwed into the rear side of the part 21. The socket device 27 is a separate piece screwed fast in the part 25, so that it does 105 not move with the part 22. The boss 23 extends forward flush with the edge of the cup-like part 21 to improve the magnetic

properties of the part 21, and the centering part 22 need not be of ferrous or other magnetic material.

What I claim as new and desire to secure 5 by Letters Patent of the United States, is:

1. A device for connecting a speed indicator to a revolving shaft comprising a magnetic part adapted to be applied endwise and adhere to the shaft so as to rotate with it 16 and engagement means for centering said part with reference to the shaft.

2. A device for connecting a speed indicator to a revolving shaft comprising a permanently magnetized steel part adapted to 15 be applied endwise and adhere to the shaft so as to rotate with it and a center punch for centering said part with reference to the shaft so associated therewith as to be movable lengthwise of the shaft with reference 20 thereto.

3. A device for connecting a speed indicator to a revolving shaft comprising a permanently magnetized steel part adapted to

be applied endwise and adhere to the shaft so as to rotate with it, a center punch for 25 centering said part with reference to the shaft associated with said part, and means also associated with said part for engaging and holding the actuating member of the speed indicator.

4. A device for connecting a speed indicator to a revolving shaft comprising a magnetic part adapted to be applied endwise and adhere to a revolving shaft so as to rotate with it, engagement means for center- 30 ing said part with reference to the shaft, and socket means for the actuating member of the speed indicator associated with said magnetic part.

In witness whereof, I have hereunto set 40 my hand this 14th day of August, 1914.

FRANK SHORT.
